UNITED STATES PATENT OFFICE.

CLYDE WEST, OF FALL RIVER, KANSAS.

CARBURETER ACCESSORY.

1,401,381.

Specification of Letters Patent. Patented Dec. 27, 1921.

Application filed January 4, 1921. Serial No. 434,944.

To all whom it may concern:

Be it known that I, CLYDE WEST, a citizen of the United States, residing at Fall River, in the county of Greenwood and State of Kansas, have invented certain new and useful Improvements in Carbureter Accessories, of which the following is a specification.

This invention relates to a device for positively maintaining carbureter choke valves in open position.

The primary object of the invention is the provision of an accessory for use upon Ford carbureters for maintaining the choke throttle therein in an open position at all times, with a minimum of liability of breakage of any parts of the accessory.

A further object of the invention is the provision of a device of the above described character which has been provided principally for use upon Ford carbureters, to supplant the spring now in use upon such carbureters for maintaining the choke throttle open, but which spring is liable to break and become permanently set. Durability, positive action, ease of attachment, adjustment and economy to manufacture being important features of the improved accessory.

Other objects and advantages will be apparent during the course of the following detailed description.

In the accompanying drawings, forming a part of this specification, and in which like reference characters designate like parts throughout the same.

Figure 1 is a side elevation of a "Ford" carbureter having the improved accessory attached thereto.

Fig. 2 is a side elevation of a detail of the invention showing the relation of the several parts of the improved accessory.

Fig. 3 is a fragmentary plan view of a detail of the invention as adapted for use upon a carbureter.

Fig. 4 is a perspective view of a detail of the improved accessory.

In the drawings, wherein for the purpose of illustration is shown a preferred embodiment of my invention, the letter A designates a carbureter, preferably of the cooling type, including a choke throttle shaft B, adapted for operation by a lever C, and which carbureter includes a flange D, provided with an attaching bolt E ordinarily placed thereon upon carbureters such as the "Ford" type. A lever operating wire F is ordinarily a part of the carbureter A, and

preferably a flexible character, although of sufficient inherent rigidity to function in connection with the improved accessory. The improved accessory G is adapted for detachable mounting upon the carbureter A for maintaining the throttle lever C in forward position at all times, whereby the choke throttle will be held open.

The accessory G comprises the bracket 10, and spiral spring 11.

The bracket 10 comprises a single piece of galvanized sheet iron or other suitable sheet metal, and is provided with a relatively large aperture 12 in one end 13 thereof, adapted for receiving the bolt E upon the flange D of the carbureter A. The end 13, is provided with an outer surface 14 concentric with the aperture 12. From the aperture 12, the bracket 10 slopes upwardly, decreasing in width as it approaches the other end 15. The smaller end 15 is provided with a relatively smaller aperture 16 and centrally of the width of the end 15. A pair of arms 17 and 18 are provided upon the end 15 and spaced from each other, a sufficient distance, that when bent to lie in parallel alignment with the main body portion of the bracket 10, they will be disposed upon either side of the aperture 16 without obstructing the entrance or exit to and from the same.

The spring 11 is an expansible spring and of good quality, due to the fact that the same will be relatively small in cross section. A convolution 20 upon an end of the spring 11 is provided for insertion intermediate the arms 17 and 18, and the main body portion of the bracket 10.

In assembling the accessory G to the carbureter A, the throttle lever operating wire F is threaded longitudinally through the spring 11 and through the aperture 16, to provide an end 21, projecting from the bracket 10, for operation of the lever C. An end 22 of the wire F is first bent inwardly substantially at right angles to the longitudinal run of the wire F and then curved outwardly as at 23, to overlie the end 24 of the lever C as is clearly shown in Fig. 3 of the drawings. The bracket 10 is then mounted upon the inside 25 of the flange D, and secured thereto by the bolt E of the carbureter A, thus compressing the spring 11 so that the lever C will be pushed forwardly and the throttle of the carbureter (not shown) will be thrown open.

The wire, as hereinbefore stated, is flexi-

ble, and the same can be reciprocated from the end 21, by further compressing the spring 11 to close the valve C, depending upon the degree which is required in the carbureter.

Should the wire 11, become permanently set, it will be merely necessary for an operator to straighten out the curve 23 of the end 22, detach the same from the lever C and 10 expand the spring 11 to the degree necessary.

The lever C is maintained in open position by means of the stop 30 abutting the post 31, rigidly mounted upon the carbureter A as 15 in ordinary construction. The open position of the throttle valve is determined by the projection 32 and in such alinement that upon operation of the lever C, the said projection 32 will abut the post 31 to define the open position of the throttle (not shown).

20 From the foregoing, it can be seen that an accessory for use upon "Ford" carbureters has been provided, which will do away with the breakage and troublesome features now found in the spring found upon said 25 carbureters. No alteration will be necessary in the carbureter structure, the same can be easily attached thereto as hereinbefore described.

It is to be understood that the form of my 20 invention herewith shown and described, is to be taken as a preferred example of the same, and that various changes in the shape, size and arrangement of parts may be made, without departing from the spirit 35 of the invention or the scope of the subjoined claims.

I claim:

1. In a throttle attachment for carbureters, the combination, with a carbureter including a choker valve operating lever, of a bracket for detachable connection to said carbureter, and an expansion spring carried by said bracket and normally maintaining said lever to open the choker valve.

45 2. As an article of manufacture, a bracket structure including a piece of sheet metal provided with a pair of spaced arms, and a spring detachably connected to said arms.

3. In a throttle attachment for carbureters, the combination, with a carbureter including a choker valve operating lever, and 50 an operating rod attached thereto, of a

bracket detachably connected to said carbureter, and loosely receiving said operating rod, and an expansion spring disposed about 55 said operating rod and engaging said operating lever and bracket to normally maintain said operating lever in forward position to hold the choker valve open.

4. In a throttle attachment for carbureters, the combination with a carbureter including a lever for operating the choke throttle valve thereof, an operating rod for said lever, and a flange having an attaching bolt thereon, of a bracket for detachably 60 mounting upon said flange by said attaching bolt, said bracket having an aperture therein for operatively receiving said operating wire, and depending arms lying parallel 65 with the main body of said bracket, and an expansion spring disposed about said operating rod and having a convolution thereof inserted intermediate said arms and main body portion of the bracket, said spring normally held under pressure intermediate 70 said bracket structure and an end of said valve operating lever for maintaining said throttle lever in forward position for maintaining the throttle open.

5. As an article of manufacture, a bracket 80 comprising a piece of sheet metal provided with a relatively large aperture in one end, and a relatively small aperture in the other, said bracket having a pair of arms upon the end adjacent said small aperture and bent 85 to lie parallel with the main portion of said bracket and upon each side of said relatively small aperture.

6. As a carbureter accessory, a bracket 90 comprising a piece of sheet metal provided with a relatively large aperture in one end, and a relatively small aperture in the other, said bracket having a pair of arms upon the end adjacent said small aperture and bent to lie parallel with the main portion of said 95 bracket and upon each side of said relatively small aperture; and a spring mounted upon said bracket having a portion thereof detachably gripped intermediate said arms and said main body portion of the bracket, 100 for securely connecting said spring to said bracket.

CLYDE WEST.
